G. A. JOHNSON.

RAILWAY DRAFT RIGGING.

APPLICATION FILED MAR. 1, 1916.

1,258,907.

Patented Mar. 12, 1918.

UNITED STATES PATENT OFFICE.

GEORGE A. JOHNSON, OF CHICAGO, ILLINOIS, ASSIGNOR TO WILLIAM H. MINER, OF CHAZY, NEW YORK.

RAILWAY DRAFT-RIGGING.

1,253,907.

Specification of Letters Patent. Patented Mar. 12, 1918.

Application filed March 1, 1916. Serial No. 81,320.

To all whom it may concern:

Be it known that I, GEORGE A. JOHNSON, a citizen of the United States, residing at Chicago, in the county of Cook and State 5 of Illinois, have invented a certain new and useful Improvement in Railway Draft-Rigging, of which the following is a full, clear, concise, and exact description, reference being had to the accompanying drawings, 10 forming a part of this specification.

This invention relates to improvements in railway draft riggings.

One object of the invention is to provide a draft rigging of high capacity and so designed that the ultimate load applied to the gear is decreased as compared with present similar constructions.

Other objects of the invention are to provide a draft rigging for railway cars where- 20 in a portion of the buffing shocks is absorbed by flexing a front follower against a friction shell member; and to also apply the ultimate load to the friction shell over a greater area and in a better manner than 25 formerly.

The invention furthermore consists in the improvements in the parts and devices and in the novel combinations of the parts and devices as herein shown, described or 30 claimed.

Figure 1 is a horizontal, sectional view showing the parts in normal position. Fig. 2 is a broken, horizontal sectional view showing the gear under full buff. And 35 Fig. 3 is a front end elevation of the friction shell.

In the drawing forming a part of this specification, 10—10 denote channel center or draft sills of usual construction, the same 40 having riveted or otherwise secured thereto rear stop lugs 11—11 and front stop lugs 12—12. The draw bar 13 is operatively connected to the friction gear A by a yoke 14 having a hooded forward end connected to 45 the draw bar as by coupler key 15, said coupler key being slidable in elongated slots 16 in the side walls of said hood and also in elongated slots 17 formed in the sills and front stop lugs 12.

50 The friction gear mechanism A, as shown, comprises a casting having a friction shell or cylinder 18 near the front end thereof and a substantially rectangular twin spring casing 19 formed integrally with the shell 55 at its rear end. The spring casing 19 is

provided with a vertical face 20 which serves as the rear follower of the gear to abut the rear stops 11. Coöperating with the friction cylinder 18 is a plurality of friction shoes 21 and wedge 120. Preliminary movement of said shoes and wedges is resisted by a spring 22 and final movement by means of twin arranged sets of nested springs 23—23 which operate through a spring follower 24 mounted with- 60 in the combined friction shell and spring casing.

Interposed between the wedge 120 and the rear end of the draw bar 13 is a front follower 25 of the usual type and, obviously, 70 upon inward movement of the draw bar the friction shoes and wedge will be actuated in a well known manner. As the front follower 25 approaches the end of its buffing movement, the side edges thereof are 75 brought into engagement with the forwardly extended side portions 26—26 of the combined friction shell and spring casing. The front wall of the casting is curved inwardly toward the center thereof as indicated at 80 27—27 so that, as inward movement of the draw bar 13 continues, the follower 25 will be flexed inwardly to the position shown most clearly in Fig. 2. From this it will be seen that during the final portion of the 85 buffing movement, not only is the friction mechanism working to absorb the shock but the follower 25 is being bent or flexed to also absorb part of the blow. Any tendency of the front follower 25 to remain permanently bent from the buffing movement will, 90 of course, be overcome by the pressure applied to the follower in draft.

From the preceding description, it will be seen that the ultimate load transmitted to 95 the casting 18—19 is less than that heretofore transmitted to friction gears of a similar type wherein the final blow was transmitted centrally to the casting by the follower through the friction shell only and 100 without flexing or bending of the front follower. Furthermore, by providing the casting A with the shoulders 26—26 at the sides of the friction cylinder 18, the final blow applied to the casting A is distributed over 105 a greater area and the entire casting presents a much stronger "column" than has heretofore been the case where the front follower has been brought to rest at the end 110 of the buffing movement against the circular

end of the friction cylinder. As will be understood by those skilled in the art, various changes and modifications may be made in the details of construction and arrangement 5 of the parts without departing from the spirit of the invention, and all such changes and modifications are contemplated as come within the scope of the claims appended hereto.

10 I claim:

1. As an article of manufacture, an integral combined friction shell and spring casing for railway draft rigging, said shell and casing being of substantially rectangular cross section throughout and having a plain transverse wall at one end adapted to coöperate with stops of a draft rigging, the opposite end of said shell and casing being concaved, said concaved end being adapted 20 to permit flexing of a follower thereagainst, said combined shell and casing acting as a column, under compression, for its full width at both ends.

2. In a draft rigging, the combination 25 with draft sills and main front and rear stops, of a casting within which is located shock absorbing means, said casting remaining stationary under buff, and a front follower for actuating said shock absorbing 30 means, said casting being provided at its front end and near the sides thereof adjacent said sills with projections adapted to engage said follower near its ends, to thereby permit said follower to be flexed between 35 its ends and against said casting during the final portion of the buffing action.

3. A draft rigging for railway cars having a combined friction shell and spring casing, friction members coöperable with

said shell, springs within said spring casing, 40 and a follower for actuating said friction members, said friction shell and casing having projections on the ends nearest said follower and adapted to engage the latter before complete actuation of the friction 45 members, the follower being flexed during the last part of the actuation and absorbing part of the shock to thereby minimize the ultimate load required to be absorbed by the friction mechanism proper.

4. In a draft rigging for railway cars, the combination with draft sills, front and rear stops, and a front follower, of a casting having a friction shell and spring casing formed therewith, friction elements coöperable with said shell and adapted to be actuated by said follower, said casting having extensions at its forward end on the sides thereof, said extensions being adapted to engage said follower near its ends prior 60 to the complete actuation of the friction mechanism, to thereby permit said follower to be flexed.

5. In a draft rigging, the combination with a combined friction shell and spring 65 casing casting, friction members coöperable with said shell and springs within said casing, of a follower arranged to actuate said friction elements, said casting on the end adjacent said follower, being provided with 70 curved faces against which said follower is adapted to flex upon final movement of the gear.

In witness that I claim the foregoing I have hereunto subscribed my name this 18th 75 day of February, 1916.

GEORGE A. JOHNSON.
